UNITED STATES PATENT OFFICE.

CHARLES E. RHINEHART, OF CORAOPOLIS, PENNSYLVANIA.

FLY-NET.

SPECIFICATION forming part of Letters Patent No. 759,470, dated May 10, 1904.

Application filed September 4, 1903. Serial No. 171,899. (No model.)

To all whom it may concern:

Be it known that I, CHARLES E. RHINEHART, a citizen of the United States, residing at Coraopolis, in the county of Allegheny and State of Pennsylvania, have invented new and useful Improvements in Fly-Nets, of which the following is a specification.

This invention relates particularly to leather fly-nets for horses, and has for its object the production of a net which may be made from small pieces of leather which would otherwise be wasted in such a manner that a strong and serviceable net will result.

The invention is characterized by improvement in respect to the manner in which the sections are cut from the stock and the manner in which they are joined together.

In the accompanying drawings, Figure 1 is a plan view of a part of a net constructed according to invention. Fig. 2 is a plan view of a blank slitted to produce the sections. Fig. 3 is a plan view of a section opened out.

The net is made by taking small pieces of leather and cutting a series of parallel slits therein from alternately-opposite edges thereof without cutting through the other edge, so that when opened out a continuous string or section is formed. The sections are then woven or interlocked together and attached to appropriate longitudinal stays or strips.

Referring specifically to the drawings, the blank 1 is slitted, as at 2. The slits run parallel and start alternately from opposite edges. They terminate short of the other edge, so that

when the blank is opened out sidewise, as indicated at Fig. 3, a zigzag strip or string is produced, forming one section of the net. These sections are interlocked together in rows by weaving the strips together, engaging each other at the angles of the zigzag, where they may be fastened or fixed by stitching or tying, as indicated at 4, or by any suitable fastening means. This produces a net of diamond-shaped mesh, as indicated in Fig. 1. At 5 longitudinal stays or strips of material, such as cotton or linen, are inserted, fastened at opposite edges to the adjacent angles of the net-sections, which serve to space the meshes and hold the sections in proper position.

It will be seen that the whole net may thus be constructed of small pieces or bits of leather, since there is absolutely no waste and no eyes or the like to cut.

What I claim as new, and desire to secure by Letters Patent, is—

A fly-net comprising rows of sections, each section being a zigzag strip, produced by cutting parallel slits in a blank, alternately from opposite edges thereof, said strips being interlaced and fastened together at the angles.

In testimony whereof I have signed my name to this specification in the presence of two subscribing witnesses.

CHARLES E. RHINEHART.
